US0D1007227S

(12) **United States Design Patent** (10) **Patent No.:** **US D1,007,227 S**
Pamplin (45) **Date of Patent:** **** Dec. 12, 2023**

(54) **PORTABLE BLENDER**(71) Applicant: **BlendJet Inc.**, Benicia, CA (US)(72) Inventor: **Ryan Michael Pamplin**, San Juan, PR (US)(73) Assignee: **BlendJet Inc.**, Benicia, CA (US)(***) Term: **15 Years**(21) Appl. No.: **29/808,024**(22) Filed: **Sep. 16, 2021****Related U.S. Application Data**

(63) Continuation of application No. 29/761,677, filed on Dec. 10, 2020, now Pat. No. Des. 931,039, which is a continuation of application No. 29/714,599, filed on Nov. 25, 2019, now Pat. No. Des. 905,496.

(51) **LOC (14) Cl.** ..... **31-00**(52) **U.S. Cl.**USPC ..... **D7/378; D7/376; D7/412; D7/413**(58) **Field of Classification Search**

USPC ..... CLAIM

The ornamental design for a portable blender, as shown and described.

DESCRIPTION

FIG. 1 is a front view of a portable blender showing the new design; and,

FIG. 2 is a front-left perspective view thereof.

The portions shown in broken lines form no part of the claimed design. The surface(s) or portion(s) of the claimed design that would normally be visible but are not shown in the drawing or described in the specification of the present application form(s) no part of the claimed design.
